UNITED STATES PATENT OFFICE

AUGUST HARTMANN, OF BARMEN, GERMANY, ASSIGNOR TO AMERICAN BEMBERG CORPORATION, OF NEW YORK, N. Y.

CENTRIFUGAL SPINNING MACHINE

Application filed September 17, 1928, Serial No. 306,470, and in Germany September 21, 1927.

This invention relates to centrifugal spinning machines for the production of artificial silk.

In such machines which are already known, one row of centrifuges is associated with a row of spinning devices. Owing to this arrangement, the number of the spinning devices and the output of the machine are limited. The object of the present invention is to provide an arrangement by means of which the output of the machine may be doubled or even increased to a greater extent.

According to the present invention, a centrifugal spinning machine for the production of artificial silk is provided with a row of spinning devices in which a greater number of such devices than usual are employed, and with two or more rows of spinning centrifuges, whilst one or more rows of guide or conveying rollers or equivalent members are associated with the said spinning devices and centrifuges. In one construction, the guide or conveying rollers are all disposed upon a single shaft and serve to guide or stretch the threads and to convey them as vertically as possible to the centrifuges, the threads being passed alternately to the first or second row of centrifuges. In this case, of course, the threads are not passed into the spinning tubes or funnels actually vertically but in a somewhat sloping direction. If it is desired to avoid this sloping path of the threads, the rollers may be arranged alternately on two parallel shafts in such a manner that the threads may be conveyed to the rows of centrifuges independently of one another and in a vertical direction. For spinning apparatus, spinnerettes immersed in an open precipitating bath, or spinnerettes in so-called spinning tubes, or spinning funnels may be employed, the latter being used for carrying out the stretch spinning process. The usual spinning devices may be employed in this case in association with acidifying apparatus. Particularly suitable spinning devices are described in Patent No. 1,682,797, granted Sept. 4, 1928.

If the stretch spinning process is being employed, when it is important to draw off the threads uniformly under tension and to take

care that the threads are introduced as vertically as possible into the centrifuges, each of the threads may be passed over two rollers. In this case, the threads may be passed first of all over a lower row of rollers and then over a second row of rollers disposed above the first row. In this manner, the path traversed by the threads is considerably lengthened, without having to increase the overall size of the machine. All the second row of rollers may be disposed on one shaft only or they may be arranged upon two shafts, those of the first row alternating with those of the second row. In the latter case, the threads may be conveyed in a vertical direction to the

The rows of centrifuges may be arranged accurately one behind the other in such a manner that the casings which protect the centrifuges fit into each other like a chessboard. In this case, it is of advantage under certain conditions to mount one of the upper rows of conveying rollers upon transverse shafts so that all the threads may be conducted into the centrifuges along their axes of rotation in spite of the limited amount of space.

One arrangement suitable for the purpose is one in which the spinning centrifuges are arranged in rows, one behind the other and alternately to each other. By this arrangement, the rear rows of centrifuges, and particularly the introduction of the threads into and changing the spinning pots or spinning pot linings, may be attended to more easily. For this purpose, the casings for the centrifuges may be formed with five sides when two rows of centrifuges are being employed, whilst if more rows of centrifuges are being employed, the casings may be six-sided, so that an arrangement similar to a honeycomb is obtained. Where several rows of centrifuges are employed, it is an advantage to arrange the centrifuges in rows upon both sides of the rows of spinning devices. The centrifuges may be also disposed in the form of steps which slope upwards.

Some forms of construction suitable for the purpose in accordance with the invention are illustrated diagrammatically by way of

example in the accompanying drawings, in which:—

Figure 1 shows a viscose spinning machine in cross-section.

5 Figure 2 another form of construction of a similar machine.

Figures 3 and 4 each one form of construction of a stretch spinning machine in cross-section.

10 Figure 5 a plan view showing the centrifuges arranged in the form of a honeycomb.

Figure 6 shows another form of construction of a stretch spinning machine in cross-section.

15 Referring first of all to Figure 1 of the drawings, illustrating a viscose spinning machine, the threads pass from the spinnerettes 1 which are supplied from the tube 2 to the spinning bath 3. From the latter, they are conveyed further by the rollers 6 which are mounted upon a single shaft and are then conveyed alternately through the funnel tubes 7 and 7' to the centrifuges 8 and 8', the latter being surrounded by protecting casings 9 and 9'.

20 Referring now to Figure 2, which shows a machine of a similar kind, the threads from the spinnerettes 1 pass over the rollers 6 to the funnel tubes 7 into the centrifuges 8, while the threads from the spinnerettes 1' pass over the rollers 6' to the funnel tubes 7' into the centrifuges 8'. It will be seen from the drawings that the rollers 6 and 6' are arranged on two parallel shafts, and the rollers 6 are arranged alternately to the rollers 6'. The individual threads may here be conveyed vertically into the axes of the centrifuges 8 and 8'.

25 In Figure 3, illustrating a machine for carrying out the stretch spinning process, the threads from the spinning apparatus 4 are conducted through the acidifying apparatus 5 and are then drawn off by the rollers 6 and 6', and are then conducted through the funnel tubes 7 and 7' into the centrifuges 8 and 8'. The threads pass conveniently around about three-quarters of the circumference of the rollers 6 and 6'.

30 In Figure 4, which illustrates a machine for the same kind of artificial silk spinning process, the threads pass from the acidifying apparatus 5 and then over the row of rollers 10 to the rows of rollers 6 and 6', these latter being arranged above the rollers 10. Each roller 6 is mounted upon a transverse shaft so as to permit the direction of the threads to be changed transversely to the plane of travel of the threads so that the threads may 35 be passed vertically into the funnel tubes 7 of the first row of centrifuges 8.

35 In Figure 5 the spinning pots 8 and 8' are arranged in rows and each spinning pot is disposed in a protecting casing which is formed with five sides. These casings can

thus fit into each other in the manner of a honeycomb.

40 In Figure 6 the threads from the acid guides 5 are drawn off by the lower row of rollers 6 and alternate threads are conducted to the rows of rollers 6' and 6'', respectively, which are mounted upon parallel shafts. The threads from the upper rows of rollers are conducted to rows of centrifuges located beneath the rows of rollers and arranged in 75 the form of steps sloping upwardly.

Having thus described my said invention, what I claim as new and desire to secure by Letters Patent is:—

45 1. In a centrifugal spinning machine, in combination, a row of spinning nozzles in which a greater number of such nozzles than usual for a given length of machine are employed, a series of centrifuges corresponding in number to the nozzles, and arranged in 80 staggered rows, and guiding means so arranged that any filaments produced by said spinning nozzles will be led vertically into the corresponding centrifuges.

50 2. In a centrifugal spinning machine for the production of artificial silk, having one row of spinning nozzles in which a greater number of such nozzles than usual for a given length of machine are employed, a plurality of rows of spinning centrifuges including a centrifuge for each spinning nozzle, two upper rows of conducting members and a lower row of conducting members for the threads associated with the spinning nozzles and centrifuges, said upper conducting members being so arranged that threads from adjacent spinning nozzles may be conducted substantially vertically into the centrifuges 95 100 105

55 3. A centrifugal spinning machine for the production of artificial silk, having one row of spinning nozzles, in which a greater number of such nozzles than usual for a given length of machine are employed, a plurality of rows of spinning centrifuges including 110 a centrifuge for each spinning nozzle, a lower row of conducting members, a row of shafts, a shaft disposed substantially at right angles to the shafts forming the row of shafts, a pair of upper rows of conducting members, the conducting members of one of said rows being mounted upon the shaft, each of the conducting members of the other row being mounted upon one of the shafts of the row of shafts, said conducting members being so arranged that threads from adjacent spinning nozzles may be conducted to centrifuges in different rows.

60 4. A centrifugal spinning machine for the production of artificial silk, having one row of spinning nozzles in which a greater number of such nozzles for a given length of machine are employed, a pair of rows of spinning centrifuges including a centrifuge for each spinning nozzle, the centrifuges in one 115 120 125

row being staggered with respect to those of the other row, five-sided casings for each of said centrifuges and arranged to fit into each other like a honeycomb, and conducting members for the threads associated with the said spinning nozzles and centrifuges, said conducting members being so arranged that threads from adjacent spinning nozzles may be conducted to centrifuges in different rows.

10 5. A centrifugal spinning machine for the production of artificial silk, having a single row of spinning funnels, means for hardening the fresh spun threads, a plurality of rows of spinning centrifuges arranged on

15 one side of the machine, the total number of said centrifuges corresponding with the number of spinning funnels, said rows being staggered with respect to each other and each centrifuge having a five sided casing adapted to fit with the other casings in the shape of a honeycomb, and means for conveying adjacent threads from said spinning funnels to centrifuges in different rows.

6. A centrifugal spinning machine for the 20 production of artificial silk, having a single row of spinning funnels, means for hardening the freshly spun threads, a plurality of rows of spinning centrifuges arranged on one side of the machine, the total number of 25 said centrifuges corresponding with the number of the spinning funnels, and two drawing rollers associated with each funnel for conveying the thread from the spinning funnels to the centrifuges, one of said drawing rollers being positioned at the level of the thread leaving the hardening means and the other being positioned at a greater elevation, said drawing rollers being so arranged that threads from adjacent spinning nozzles 30 may be conducted to centrifuges in different rows.

In testimony whereof, I have signed my name to this specification this 4th day of September, 1928.

AUGUST HARTMANN.
